JOHN M. FEDDERS, OF BUFFALO, NEW YORK, ASSIGNOR TO FEDDERS MANUFACTURING COMPANY, INC., OF BUFFALO, NEW YORK, A CORPORATION OF NEW YORK.

RADIATOR CORE.

Application filed June 10, 1925. Serial No. 36,131.

This invention relates to a core for radiators designed more particularly for use in connection with the cooling system of an automobile gas engine and has for its main object the provision of a core for this class of radiators which is strong and durable, which has a larger radiating capacity and which can be manufactured at comparatively low cost.

10 This invention is an improvement on the radiator core shown and described in my application for Letters Patent No. 8556 filed February 11, 1925.

In the accompanying drawings:—

15 Fig. 1, is a front elevation, partly in section of a radiator embodying my improvements.

Fig. 2, is a horizontal section of the same taken on line 2—2, Fig. 1.

20 Fig. 3, is a fragmentary horizontal section, on an enlarged scale, taken on the line 3—3 of Fig. 1.

Fig. 4, is a fragmentary horizontal section, on an enlarged scale, taken on the line 4—4 of Fig. 1.

Fig. 5, is a fragmentary perspective view of one of the radiating plates.

Fig. 6, is a fragmentary vertical section taken on line 6—6, of Fig. 1.

30 Similar characters of reference indicate like parts throughout the several views.

The numerals 20 and 21 represent the upper and lower water boxes or headers which may be connected with the supply and return pipes of the gas engine cooling system in any suitable and well known manner.

Between the headers is arranged the cooling core of the radiator which consists essentially of a plurality of upright water tubes 22 communicating at their upper ends with the bottom of the upper header and at their lower ends with the top of the lower header, and a plurality of horizontal air passages 23, 24 arranged between adjacent water tubes and extending from the front side to the rear side of the radiator.

Each of the water tubes is constructed of a single sheet of metal which is bent to form two upright flat parallel longitudinal walls 25, a rear turn 26 connecting the rear edges of said walls, two inwardly off-set flanges 19 arranged at the front edges of said walls and connected together by soldering or otherwise to form a water tight joint therebetween, and horizontal end flanges 27 ar-

ranged at the upper and lower ends of the walls and offset flanges and projecting laterally from opposite sides of the tube.

A plurality of tubes of this character are arranged in a transverse row between the upper and lower headers and spaced suitable distances apart. The upper and lower flanges of each tube have their longitudinal edges connected with the corresponding edges of the upper and lower flanges of adjacent water tubes so as to form in effect a plate at the upper end of the tubes which is secured by soldering or otherwise to the upper header and closes the bottom thereof and a plate at the lower ends of the tubes 70 which is secured by soldering or otherwise to the lower header so as to form the top thereof.

Along opposite outer sides of the walls of each water tube are arranged two spacing 75 strips of sheet metal which are corrugated. The two strips are formed of a single sheet of metal which is bent so that the two sections form two corrugated strips which are folded or doubled so that the same are arranged side by side and are connected at one pair of their corresponding longitudinal edges while the opposite pair of their corresponding longitudinal edges are disconnected but oppose each other. When the metal 80 sheet is thus folded each of its corrugated strips forms an inner set of corrugations and an outer set of corrugations and the summits 35 of the inner set of corrugations oppose each other so as to form a vertical row 85 of said air passages 23 while the outer summits 36 of the outer set of corrugations are opposed to the corresponding summits of the outer corrugations of spacing strips associated with adjacent water tubes and form 90 therewith vertical rows of said air passages 24.

The central or intermediate parts of the summits 35 of the inner set of corrugations are offset laterally, as shown at 37, so that 100 such offsets on companion summits 35 together form a tubular seat while the end portions 38 of these summits next to the connecting turn between the two spacing strips and the end portions 39 of these summits at 105 the disconnected edges of these strips oppose each other in rear and in front of the respective water tubes.

One of these water tubes is seated at intervals throughout its length in the tubular 110

seats between the opposing summits of the inner corrugations of the two strips arranged on opposite sides of this tube and the latter also traverses the air passages 23 formed between these strips so that the air in passing through said passages will come in direct contact with the portions of the tube exposed in said passages and carry away the heat which is transmitted to the same from the water passing through the tubes.

The disconnected front edges of the two spacing strips associated with each water tube are preferably connected by soldering 15 with the outer sides of the longitudinal flanges 19 of this tube.

In order to increase the transmission of heat to the air, radiating wings, tongues or baffles 18, 40, 41, 42 are struck out of the 20 body of the sheet metal forming these strips so that the same project laterally from these strips into the path of the air as the same passes through the air passages and intercepts the air. For the purpose of holding 25 the several water tubes and spacing strips in position relative to each other at the rear of the core and increasing the strength of the same so that it is capable of sustaining the shock and strain to which it is subjected 30 while in use, means are provided for connecting the opposing spacing strips of adjacent water tubes. This is preferably accomplished by providing the rear parts of the 35 summits of the outer corrugations with lips, wings or tongues 44, 45, which preferably incline in opposite directions, the lips 44 in this instance inclining backwardly and the lips 45 forwardly, and the lip 44 on the spacing strip associated with one water tube 40 interlocking by a wedging engagement with the lip 45 on the spacing strip of an adjacent water tube, as shown in Figs. 2 and 4. By this means the rear parts of the spacing 45 strips on adjacent tubes are firmly drawn against each other and secured together mechanically without the use of solder. These interlocking lips or wings further add to the baffling effect on the air to induce the latter to absorb the greatest amount of heat 50 contained in the water.

In order to still further increase the transference of heat from the water in the water tubes to the air passing through the air passages auxiliary means are provided which 55 are constructed as follows:

The numeral 50 represents a plurality of upright radiating strips or plates of sheet metal, each of which is arranged lengthwise between the opposing spacing strips of 60 two adjacent water tubes. Each of these radiating strips is engaged on its opposite sides by the outer summits 36 of the outer corrugations of two opposing spacing strips and is firmly gripped therebetween so as to 65 produce a good metallic contact therewith

and thereby enable the radiating strip to take some of the heat from the respective spacing strips and transfer it to the air which comes into contact with opposite sides of the respective radiating strip.

In order to permit the locking wings, lips or tongues 44, 45 on the rear parts of the summits of adjacent spacing strips to engage with each other, the adjacent rear part 70 of each radiating strip is provided with a vertical row of clearance openings 51, through which the inclined lips 44, 45, project and engage with each other so as to draw the respective spacing strips by a wedge action against opposite sides of the 75 radiating strip, as shown in Figs. 1 and 4. The lips, therefore, not only interlock the spacing strips but also interlock with the radiating strip therebetween and hold the latter against displacement.

By thus arranging a radiating strip between the outer summits of adjacent corrugated spacing strips each air passage 24 is divided into two sections and splits the stream of air passing therethrough into two 80 jets which impinge against opposite sides of the respective radiating strip and thus increase the radiation of heat to the air accordingly.

For the purpose of increasing the heat 85 radiating capacity of the radiating strips each of these strips is provided with a plurality of wings or lugs 52 which are struck out of the body of this strip within the air passages 24 and project laterally therefrom so as to intercept the streams of air passing through the core. These wings or lugs 52 are preferably arranged in longitudinal 90 rows and the members of each row project alternately from opposite sides of the respective radiating strip, as shown in Figs. 3 and 5. These wings or lugs in each row 95 also preferably project alternately upwardly and downwardly and thus tend to uniformly obstruct the air passing through the 100 passages 24 and thereby obtain the maximum radiating efficiency.

I claim as my invention:

1. A radiator comprising a plurality of 115 water tubes and a plurality of air passages arranged between adjacent water tubes, each of said water tubes having opposite sheet metal walls, two spacing strips of corrugated sheet metal arranged on opposite sides of each water tube and each spacing strip having alternating inner and outer summits, the inner summits of said strips engaging opposite sides of a water tube, and a plurality of radiating strips of sheet metal each arranged between the outer summits of two 120 opposing spacing strips of adjacent water tubes, each radiating strip being provided with a plurality of locking openings, and the adjacent parts of the outer summits of the respective spacing strips being provided 125

with interengaging inclined locking lips which project through said openings of the radiating strip.

2. A radiator comprising a plurality of water tubes and a plurality of air passages arranged between adjacent water tubes, each of said water tubes having opposite sheet metal walls, two spacing strips of corrugated sheet metal arranged on opposite sides of each water tube and each spacing strip having alternating inner and outer summits, the inner summits of said strips engaging opposite sides of a water tube, and a plurality of radiating strips of sheet metal each arranged between the outer summits of two opposing spacing strips of adjacent water tubes, each radiating strip being provided with a plurality of locking openings, and the adjacent parts of the outer summits of the respective spacing strips being provided with interengaging inclined locking lips which project through said openings of the radiating strip and said radiating strips being provided between adjacent outer summits of the corrugated spacing strips with radiating wings which are struck out of the metal of said radiating strips.

3. A radiator comprising a plurality of water tubes and a plurality of air passages arranged between adjacent water tubes, each of said water tubes having opposite sheet metal walls, two spacing strips of corrugated sheet metal arranged on opposite sides of each water tube and each spacing strip having alternating inner and outer summits, the inner summits of said strips engaging opposite sides of a water tube, and a plurality of radiating strips of sheet metal each arranged between the outer summits of two opposing spacing strips of adjacent water tubes, each radiating strip being provided with a plurality of locking openings, and the adjacent parts of the outer summits of the respective spacing strips being provided with interengaging inclined locking lips which project through said openings of the radiating strip and said radiating strips being provided between adjacent outer summits of the corrugated spacing strips with radiating wings which are struck out of the metal of said radiating strips.

radiating wings which are struck out of the metal of said radiating strips and which project alternately in opposite directions.

4. A radiator comprising a plurality of water tubes and a plurality of air passages arranged between adjacent water tubes, each of said water tubes having opposite sheet metal walls, two spacing strips of corrugated sheet metal arranged on opposite sides of each water tube and each spacing strip having alternating inner and outer summits, the inner summits of said strips engaging opposite sides of a water tube, and a plurality of radiating strips of sheet metal each arranged between the outer summits of two opposing spacing strips of adjacent water tubes, each radiating strip being provided with a plurality of locking openings, and the adjacent parts of the outer summits of the respective spacing strips being provided with interengaging locking lips which project through said openings of the radiating strip.

5. A radiator comprising a plurality of water tubes and a plurality of air passages arranged between adjacent water tubes, each of said water tubes having opposite sheet metal walls, two spacing strips of corrugated sheet metal arranged on opposite sides of each water tube and each spacing strip having alternating inner and outer summits, the inner summits of said strips engaging opposite sides of a water tube, and a plurality of radiating strips of sheet metal each arranged between the outer summits of two opposing spacing strips of adjacent water tubes, each radiating strip being provided with a plurality of locking openings, and the adjacent parts of the outer summits of the respective spacing strips being provided with interengaging locking lips which project through said openings of the radiating strip and said radiating strips being provided between adjacent outer summits of the corrugated spacing strips with radiating wings which are struck out of the metal of said radiating strips.
